CLAIM

The ornamental design for a carousel, as shown and described.

DESCRIPTION

The figures show an ornamental design for a carousel.

FIG. 1 is a front, top isometric view of a carousel showing the design;

FIG. 2 is a front elevational view thereof;

FIG. 3 is a back elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a front, bottom isometric view thereof.

1 Claim, 8 Drawing Sheets(56)
